(57) **CLAIM**

The ornamental design for an illuminated post cap having a dual lighting effect, as shown and described.

DESCRIPTION

FIG. 1 is a perspective view of a first embodiment of the post cap in an unilluminated state;

FIG. 2 is a front elevation of the cap shown in FIG. 1, the rear elevation being identical thereto;

FIG. 3 is a right-side elevation of the cap shown in FIG. 1, the left-side elevation being identical thereto;

FIG. 4 is a top plan view of the cap shown in FIG. 1;

FIG. 5 is a bottom plan view of the cap shown in FIG. 1;

FIG. 6 is a perspective view of the post cap in an illuminated state;

FIG. 7 is a perspective view of a second embodiment of the post cap of FIG. 1, the only difference being the size of the base, it being understood that all other surfaces are the same as those of the first embodiment;

FIG. 8 is a perspective view of a third embodiment of the post cap of FIG. 1, the only difference being the size of the base, it being understood that all other surfaces are the same as those of the first embodiment; and,

FIG. 9 is a perspective view of a fourth embodiment of the post cap of FIG. 1, the only difference being the size of the base, it being understood that all other surfaces are the same as those of the first embodiment.

The broken lines shown in the figures represent portions of the illuminated post cap and post that form no part of the claimed design. The dash-dot lines shown in FIG. 6 indicate illumination emanating outwardly from the front, rear and sides of the illuminated post cap. The dash-dot-dot lines shown in FIG. 6 indicate illumination emanating downwardly from the bottom of the illuminated post cap.
